Nos. 804

G. Smith, H. Brown and J. A. Read of Philadelphia, Pa.
Assignors to J. G. Abbott, & Archibald Lawrence, of the same place
Letters Patent No. 804, Dated June 17th 1856.

The schedule referred to in these Letters Patent, and making part of the same—

To all whom it may concern,

Be it known that we, Garretson Smith, Henry Brown, & Joseph A. Read, of the City & County of Philadelphia, and State of Pennsylvania, have produced a new & original

Design for a nine plate stove.

And we do hereby declare that the following is a full, clear, & exact description ^{of the same}, reference being had to the annexed drawing, forming part of this specification; in which

Figure 1. is a front elevation.

Figure 2. is a side elevation.

Figure 3. is a rear elevation.

Figure 4. is an elevation of stove support.

The front plate A, has on its lower part the feed door B, which is ornamented, in bas-relief, by figure a. foliage b. & a molding c, terminating in foliage d. It also has an ornamental latch e. Above the door is an ornament consisting of a tablet raised above the plate by a molding f, terminating in sweeping foliage g; upon the tablet is a central figure h, from which issues foliage i.

On each side of the door B. & the ornamental figure, is an ornamental border, made up of a raised surface j, and projections k.

At the top of the plate is the inscription "Patented 1856" in raised capitals and numerals. The precise design, configuration and arrangement of the above specified ornaments in bas-relief, is as set forth in fig 1.

The back plate C, has two borders D, made up like those of front plate A, between which is a raised panel E, of irregular form, which

Pls 804

is ornamented in bas-relief by central figure l and foliage m, the design, configuration and arrangement being as shown in figure 3.

The side plate G, bears the over door H and panel I. The former is embellished with the panel P, raised by a moulding m, the corners of which terminate in foliage n. Upon the panel is a figure in bas-relief, made up of central piece p and sweeping foliage q; the design, configuration and arrangement, being as shown in figure 2.

The panel I, has a moulding J, similar to door H, and bears an ornament in bas-relief made up of central figure r and foliage S, similar to that on door H; the precise design, configuration and arrangement being as shown in fig 2.

The support P', has the form shown in figure 4.

We claim the design, configuration and arrangement of the several ornaments and mouldings, and form of support of the nine plate stove, as above set forth and represented in the drawings.

In testimony whereof, we have hereunto signed our names before two subscribing witnesses.
